CLAIM

The ornamental design for a “scope mount for attachment to a firearm barrel,” as shown and described.

DESCRIPTION

FIG. 1 is a perspective view of a “scope mount for attachment to a firearm barrel,” showing my new design from the left front;

FIG. 2 is a front elevational view thereof;

FIG. 3 is a rear elevational view thereof;

FIG. 4 is a top plan view thereof;

FIG. 5 is an elevational view of the right side of the scope mount, and the opposite side view being a mirror image thereof; and,

FIG. 6 is a bottom plan view thereof.
